UNITED STATES PATENT OFFICE.

ERWIN EHRHARDT, OF HERMSDORF, NEAR BERLIN, GERMANY, ASSIGNEE TO SIEMENS & HALSKE, AKTIENGESELLSCHAFT, OF SIEMENSSTADT, NEAR BERLIN, GERMANY, A GERMAN CORPORATION.

TELEGRAPHIC TRANSMITTER.

Application filed November 23, 1920. Serial No. 426,061.

(GRANTED UNDER THE PROVISIONS OF THE ACT OF MARCH 3, 1921, 41 STAT. L., 1313.)

To all whom it may concern:

Be it known that I, ERWIN EHRHARDT, a German citizen, and residing at Hermsdorf, near Berlin, Germany, have invented 5 certain new and useful Improvements in Telegraphic Transmitters, of which the following is a specification.

The invention relates to an arrangement for telegraphic transmitters of the kind in 10 which the different signals which may be given in succession on the keyboard at non-uniform rate of speed, are accumulated, to be subsequently sent over the line in the same succession but at a uniform rate of 15 speed. An arrangement of this kind has the advantage that the operator is not bound to keep exactly in step with the speed of the transmission over the line, usually effected by motor driven devices, but that nevertheless 20 the line is utilized in the best manner. In arrangements of this kind as hitherto constructed the accumulating device is of mechanical construction. It usually consists of a drum provided with pins which 25 are arranged in groups so as to correspond to the individual signals to be sent in succession and which are set by the key on the keyboard according to the kind of signal and the contacts are closed corresponding 30 to the setting of the pins, which contacts effect the transmission of the signals set in the accumulating device in uniform succession over the line. This mechanical arrangement of the accumulating device consists of a great number of removable individual parts and is therefore complicated 35 and liable to disturbance during the operation.

Even devices, heretofore used, which take 40 advantage of condenser charges and discharges as means for storing up the signals, require the operator to work in full synchronism with the automatic device which transfers the stored signals to the line at 45 uniform speed, in order to utilize the line to the best efficiency.

These disadvantages are overcome according to the present invention by making use of an accumulating arrangement whose 50 speed is solely dependent upon the sending speed of the operator, and which consists of electric condensers arranged in groups, which when the key is depressed are charged 55 successively at the operator's speed in one sense or the other in a suitable combination, this device operating in conjunction with a power controlled device by which these condensers are subsequently discharged over the line for the transmission of the signal at a uniform rate of speed controlled by 60 the driving power. Such a device is practically subject to no wear at all so far as the accumulating feature is concerned and is very reliable in operation, since the accumulators involve no moving parts. Of 65 course, the operator, for practical reasons, should not have unlimited liberty in choosing his operating speed but he is bound by a special device within certain reasonable limits, though within these limits he may 70 choose his speed at will.

In the drawings Figure 1 diagrammatically shows a constructional form of the invention by way of example. Figure 2 75 illustrates a detail.

The new transmitting apparatus substantially consists of three parts that is to say a key board A, an accumulating device B, and a transmitter C. The accumulating device and the transmitter are shown in 80 Figure 1 as being turned at an angle of 90° to the shafts connected therewith for the purpose of representing the whole arrangement in one diagrammatic view. For the sake of clearness all sliding contacts 85 for supplying the electrical current to movable parts are omitted in this figure. Such parts will be apparent from Figure 2 showing an end view of the accumulating device as well as of the transmitter. For the same 90 reason the transmission of only three signals will be explained. The transmission of the three signals is effected by operating the one or the other of two keys 1 and 2, or both simultaneously. Accordingly, the 95 accumulating device B consists of two stationary contact rings 3 and 4 over which slide brushes 5, 6 and 7, 8 provided on two contact arms 9 and 10, respectively. The brushes 5, 6 and 7, 8 are connected by 100 means of collecting rings 80 (Fig. 2) with the associated parts of the system as will be explained afterwards. The contact arm 10 is rotated by a pawl and ratchet mechanism 12, 13 actuated by an electro-magnet 11. The contact arm 9 is connected 105

with a shaft 14 operated by a motor 19 through a gear wheel 15 and pinion 16 and a clutch 17, 18. The motor 19 simultaneously conveys movement to the contact arm 22 of the transmitter C provided with brushes 20, 21. The brushes 20, 21 of this transmitter are connected with the system by slip rings 81 and slide on two contact rings the one of which is provided with 10 two contact-pieces 23, 24 and the other with one contact-piece 25. The gearing 15, 16 is such that the contact arm 9 performs one sixth revolution during one complete revolution of the contact arm 22. The six 15 contact-pieces 43, 44; 50, 51, . . . of the rings 3, 4 of the accumulating device B are connected with the one coating of condensers 45, 47; 52, 53, . . ., respectively, the other coatings of which are connected with 20 a contact 27 of the key board A and a neutrally adjusted polarized line-relay R, so that they are also in communication with the transmitter C. The armature 28 of the relay R is connected with the line L 25 so that it may be connected with the battery 29 or 30. The keys 1 and 2 operate together with contacts 31, 32; 33, 34, respectively, which connect the key-levers with the positive or negative terminal of a split 30 battery 35. When operating any one of the keys another contact 36 is closed in addition to the contact 27 whereby a circuit through a battery 37 and an electromagnet 11 is established. The clutch 17, 18 between 35 the motor 19 of the transmitter C and the accumulating device B is operated by an armature lever 40 actuated by electromagnets 38, 39. The clutch 17, 18 will be thrown in and out of gear according to 40 whether electromagnet 39 or 38 is energized.

The operation of the transmitter is, as follows:

The key 1 being depressed the key-lever will engage the lower contact 32. Thus the 45 key-lever will become disconnected from the positive terminal and connected with the negative terminal of the battery 35. At the same time the contacts 27 and 36 will be closed since the movable axis 41 of these 50 contacts will be turned by means of lugs 42 at the key-levers. Assuming the brushes 5, 6 of the contact arm 10 of the accumulating device B are touching the contact pieces 43, 44 the following circuits are established:

55 from the negative terminal of the battery 35 over contact 32, key-lever 1, brush 5, contact-piece 43, condenser 45, connection 46, contact 27 to the middle of the split battery 35, and from the positive terminal 60 of the battery 35 over contact 33, key-lever 2, brush 6, contact-piece 44, condenser 47, connection 46, contact 27 to the middle of the split battery 35. Therefore, the condensers 45 and 47 are supplied with current and charged with opposite polarities.

At the same time by the contact 36 a circuit is closed through the battery 37 and the electromagnet 11. This attracts its armature 48 and moves the pawl 12 downwards which engages the adjacent tooth 70 of the ratchet wheel 13. When the key 1 is released the contacts operated thereby are opened and the circuit through the electromagnet 11 is broken. Therefore, the armature 48 and the pawl 12 will be moved upwards by a spring 49 thereby rotating the contact arm 10 in the direction of the arrow 75 until the brushes 5, 6 get into connection with the contact-pieces 50, 51 of the rings 3, 4. The condensers 45, 47 now remain 80 in the charged condition which they attained by the operation just described.

If now for transmitting the following signal both keys 1 and 2 are depressed the 85 following circuits are established: from the negative terminal of the battery 35 to contact 32, key-lever 1, brush 5, contact-piece 50, condenser 52, connection 46, contact 27 to the middle of the battery 35, and from the negative terminal of the battery 35 to 90 contact 34, key-lever 2, brush 6, contact-piece 51, condenser 53, connection 46, contact 27 to the middle of the battery 35. Therefore, the two condensers 52, 53 are charged with the same polarity. The operation of the electro-magnet 11 and pawl 12 as well as the rotary movement of the contact arm 10 takes place in the manner 95 above described.

Thus, the condensers connected with the 100 contact-pieces of the contact rings 3 and 4 may be charged with different polarities and, accordingly, the signals produced by the keys in the key-board accumulated. The transmission of the signals over the line L 105 is effected, as follows:

Assuming, the condensers 54, 55 have been charged over the brushes 5, 6 of the contact arm 10 with different polarities, as for instance, the condenser 54 with a positive 110 and the condenser 55 with a negative charge. If now the brushes 7, 8 of the contact arm 9 get into connection with the contact pieces 56, 57, the brush 21 of the transmitter arm 22 touches the contact piece 115 23 of the transmitting device C. Therefore, the following circuit is established: contact-piece 23, brush 21, line relay R, connection 46, condenser 54, contact-piece 56, brush 7, connection 60, contact-piece 23. The condenser 54 becomes discharged and the line-relay R actuates its armature 28 in accordance with this operation of the condenser 54. Accordingly, an impulse 120 from the battery 29 will be sent into the line L. When the brush 21 gets in connection with the contact-piece 24 the circuit of the condenser 54 is broken and the discharging circuit of the condenser 55 closed 125 over brush 8, connection 61, contact-piece 130 24.

24, brush 21, relay R and connection 46. The line relay R will, therefore, actuate its armature 28 so as to connect the line L with the battery 30.

5 The inner contact-ring of the transmitter C will only come into operation if the brush 20 is passing its contact 25 and the brush 21 has become inoperative. It serves switching purposes in case the two contact arms 9 and 10 interfere with each other in their operation. If, for instance, the operator in attending to his service at the key board gives a number of signals more quickly than the line transmitter will be able to transmit a 15 contact spring 66 of the arm 10 gets into connection with a contact-piece 67 provided at the hub 68 of the contact arm 9. In this case a circuit is established from battery 37, contact spring 66, contact-piece 67, connection 78, electromagnet 69, incandescent lamp 26 to battery 37. The lamp 26 is lighted and the electromagnet 69 attracts its armature 70 thereby moving a locking bar 71 in the path of the keys. Therefore, the keys become inoperative until by the further movement of 25 the contact arm 9 the contact 67 gets out of connection with the contact spring 66 so that the electro-magnet 69 becomes de-energized, the locking bar 71 released and the 30 lamp 26 extinguished, thereby indicating to the operator that he may attend to his service again.

If, on the other hand, the operator is too slowly in giving signals the contact arm 9 will so quickly advance compared with contact arm 10 that a contact-piece 73 provided in the hub 68 gets into connection with the contact-spring 66. A circuit is established, thereby, from battery 37 to spring 66, contact-piece 73, connection 74, electromagnet 38, brush 20, contact-piece 25, connection 75 to battery 37. The electromagnet 38 is energized and attracts its armature 40 so that the clutch-portions 17, 18 become disengaged and the contact arm 9 of the accumulating device B disconnected from the motive power of the line-transmitter C. The clutch-portions 17, 18 become engaged again by means of another contact-piece 76 in the hub 68. At the next step of the arm 10 this contact-piece 76 comes into connection with the spring 66, whereas the contact-piece 73 is released. Therefore, a circuit is established from battery 37 to spring 66, contact-piece 76, connection 77, electromagnet 39, brush 20, contact-piece 25, connection 75 to battery 37. The electromagnet 39 is energized and the clutch-portions 17, 18, are thrown into gear so that the contact arm 9 will take up its normal operation again. The contact-pieces 67, 73 and 76 are connected with collecting rings 82, the brushes of which are electrically connected with the associated parts of the system. The collect-

ing ring 83 supplies current to the brush 66. 65
I claim:

1. In a telegraphic transmitter, a line, means for supplying current for producing signals, a keyboard and a signal accumulating device, comprising a plurality of groups 70 of condensers electrically associated with said keyboard according to the composition of the individual signals represented on the board, means for permitting the separate charging of said individual condenser groups 75 successively at a non-uniform rate of speed depending on the operating speed of the keyboard, a sending device adapted to transmit signals to the line, said device operating at a uniform rate of speed, and means controlled by the sending device for successively discharging said condensers at a uniform rate of speed into said sending device, to cause the signal transmission to the line at a uniform speed rate. 80 85

2. In a telegraphic transmitter, a line, means for supplying current for producing signals, a keyboard and a signal accumulating device, comprising a plurality of groups 90 of condensers electrically associated with said keyboard according to the composition of the individual signals represented on the board, means for permitting the separate charging of said individual condenser groups successively at a non-uniform rate 95 of speed depending on the operating speed of the keyboard, a sending device adapted to transmit signals to the line, said device operating at a uniform rate of speed, and means controlled by the sending device for successively discharging said condensers at a uniform rate of speed into said sending device, to cause the signal transmission to the line at a uniform speed rate, and means for limiting the lag and lead of the keyboard 100 speed relatively to the line sending speed. 105

3. In a telegraphic transmitter, a line, means for supplying current for producing signals, a keyboard and a signal accumulating device, comprising groups of contact 110 segments, a group of condensers connected to each segment group, a group of brushes equal in unit size to the size of said segment groups and cooperating with the segments thereof, and suitably operated by and electrically connected with said keyboard to successively pass over said segment groups at the speed rate at which the signals are given on the board, to cause the charging of said condensers from said current supply means 115 in accordance with the character of the signal desired, a sending device operating at a uniform rate of speed and adapted to successively receive the discharge currents of said condensers for transmission to the line 120 at a uniform speed rate, and a second group of brushes similar in size to the first group 125 and cooperating with said segment groups

and mechanically operated by and in a fixed time relation to said sending device, said brushes adapted to connect said condenser groups for discharge successively 5 with said sending device.

4. In a telegraphic transmitter, a line, means for supplying current for producing signals, a keyboard and a signal accumulating device, comprising groups of contact 10 segments, a group of condensers connected to each segment group, a group of brushes equal in unit size to the size of said segment groups and cooperating with the segments thereof, and suitably operated by and 15 electrically connected with said keyboard to successively pass over said segment groups at the speed rate at which the signals are given on the board, to cause the charging of said condensers from said current supply 20 means in accordance with the character of the signal desired, a sending device operating at a uniform rate of speed and adapted to successively receive the discharge currents of said condensers for transmission to 25 the line at a uniform speed rate, and a second group of brushes similar in size to the first group and cooperating with said segment groups and mechanically operated by and in a fixed time relation to said sending 30 device, said brushes adapted to connect said condenser groups for discharge successively with said sending device, means for breaking the mechanical connection between said sending device and said second group of 35 brushes when the keyboard speed lags behind the sender speed beyond predetermined limits, and means for blocking the opera-

tion of said keyboard when the keyboard speed leads the sender speed beyond predetermined limits.

5. In a telegraphic transmitter, a line, means for supplying current for producing signals, a keyboard and a signal accumulating device, comprising groups of contact segments, a group of condensers connected to each segment group, a group of brushes equal in unit size to the size of said segment groups and cooperating with the segments thereof and suitably operated by and electrically connected with said keyboard to successively pass over said segment groups at the speed rate at which the signals are given on the board, to cause the charging of said condensers from said current supply means in accordance with the character of the signal desired, a sending device comprising a line relay adapted to send current impulses of varying polarity into said line, and a distributor controlling the energizing of said relay and adapted to operate at a uniform rate of speed, a second group of brushes similar in size to the first group and gliding over said segment groups and mechanically operated by and in fixed time relation to said distributor, said brushes adapted to connect said condenser groups for discharge successively to said distributor to energize said line relay at a uniform rate of speed and in accordance with the polarity of the condenser discharge currents.

In testimony whereof I affix my signature.

ERWIN EHRHARDT.
